(57) **CLAIM**

The ornamental design for a lavatory pedestal, as shown and described.

DESCRIPTION

In a preferred embodiment, the nature of this product is a plumbing fixture, such as a pedestal for a lavatory.

FIG. 1 is a top, right, front perspective view embodying my design;

FIG. 2 is a front elevational view thereof;

FIG. 3 is a right side elevational view thereof, the left side elevational view thereof being a mirror image of the right side shown;

FIG. 4 is a top plan view thereof;

FIG. 5 is a rear elevational view thereof; and,

FIG. 6 is a bottom plan view thereof.

The broken line representations of rear and internal structure in FIGS. 1 and 3-6 are for the purpose of illustration only, and form no part of the claimed design.
